UNITED STATES PATENT OFFICE.

BENJAMIN E. VALENTINE, OF BROOKLYN, NEW YORK.

CARTRIDGE.

SPECIFICATION forming part of Letters Patent No. 228,494, dated June 8, 1880.

Application filed April 8, 1880. (No model.)

To all whom it may concern:

Be it known that I, BENJAMIN E. VALENTINE, division inspector of rifle practice of the National Guard of the State of New York, a citizen of the United States, and residing in the city of Brooklyn, county of Kings, and State of New York, have invented a new and useful Improvement in Cartridges for Breech-Loading Guns; and I do hereby declare that the following specification, taken in connection with the drawings accompanying the same, is a full, clear, and exact description of said invention, which will enable others skilled in the art to which it appertains to make and use the same.

In the drawings, Figure 1 shows a longitudinal section of my improved cartridge, and Fig. 2 is an end view of the primed end thereof.

Similar letters indicate corresponding parts in the two figures.

My invention has for its object economy in the use of fixed ammunition for rifles.

Military rifles are usually made with a caliber larger than that of sporting-arms, and often are made to carry a ball of .50 caliber and upward. Cartridges ordinarily used in such rifles contain a comparatively large amount of powder—e. g., seventy grains in arms adopted by some of the states, which amount of powder is sufficient to carry a ball, say, five hundred and fifty grains in weight a distance from half a mile to a mile.

In the instruction of troops in armories, and in the practice by those who use such weapons in galleries and at short ranges, the use of the regulation cartridge is objectionable for several reasons: First, the size of the same makes the expense of cartridges consumed much greater than the expense of those ordinarily used for galleries and short-distance practice; second, the quantity of powder used therein throws the bullet with such force at short range as to cause rapid destruction of the targets, and also tends to shatter the ball by the force of the impact on a metallic target; third, the explosion of so large an amount of powder produces a noise and amount of smoke objectionable in a gallery or armory and a subject for complaint to those living in the immediate vicinity.

The attempt to substitute weapons of small

bore or of a sporting character is objectionable, inasmuch as, aside from the expense thereof, the items of weight, shape, trigger-pull, and action are materially different from those of the arms with which troops should be taught to practice.

My invention has for its object the production of a compound cartridge which can be used in a rifle of large caliber to throw a ball adapted to the caliber of the gun, with charges of powder fixed in shells of smaller caliber, which can be varied at any time to suit the distance and the amount of force required.

In the drawings, A represents the outer shell of my compound cartridge, which, in its outer configuration, corresponds substantially with the shape of the ordinary metallic shell used for the chamber of the rifle. I prefer to have this made of steel, to avoid the liability to crack or expand to which an inferior or softer metal might be liable.

At the end *h* of the shell in which the ball is usually seated the metal is removed or bored out of a diameter adapted to the bullet required by the caliber of the rifle, and to a depth adapted to the longest bullet which it is desired to use.

The charge of powder which is used is contained in a supplemental blank cartridge, 80 (shown in the drawings at C,) this cartridge being of the ordinary style of fixed ammunition, but made without a bullet, a pasteboard or other wad, 1, being inserted in place of the bullet to retain the powder.

The shell A is bored from its head *g*, to form an aperture of a diameter corresponding with the blank cartridge C, which it is intended to use for the charge of powder, and this aperture is bored clear through the metal till it meets the aperture bored for the bullet. This will leave an angular shoulder or seat, (shown in the drawings at *e*,) which may be, if desired, reamed out, so that said shoulder shall taper. This outer shell, A, must be made of material which is substantially inexpandible.

In a cartridge which is to be used but once the shell is generally composed of thin brass, which is liable to expand by the explosion of the powder, and unless the shell which is described in the present specification is made of a substantially solid and inexpandible material

the successive explosions of powder therein will expand the same, so as to prevent its being inserted and withdrawn from the chamber of the gun, and also will, by yielding to the explosions of the inner or supplemental cartridge, allow them to expand so as to be unable to withdraw the same, when exploded, from the outer shell.

The operation of my improved cartridge is as follows: Taking a shell made for a .50 caliber rifle, for instance, I find blank cartridges of the caliber known as "No. 32" a convenient size. These cartridges may be of any desired length, according to the distance which it is desired to throw the ball. Taking the empty shell A, a blank cartridge C, is inserted in the aperture at the head of the shell till its head G is flush with the end of the shell gg. If a short cartridge is used, and the air-space left between the end of the blank cartridge C and the ball B is deemed objectionable, it may be filled with sawdust or wads of pasteboard or felt jj. A ball, B, of the caliber of the rifle is then inserted at the end hh, and if a light and short ball is used the same may be forced down to the shoulder at e; or, if desired, the space between the bullet and shoulder may be filled with sawdust or wads. A compound cartridge is then produced, which may be inserted in the chamber of the gun and fired like an ordinary cartridge, with the result, however, of less noise, less smoke, and greatly lessened expense.

If the blank cartridges C which are used are center-fire cartridges with a primer, p, it is obvious that the shells can be saved and re-loaded as blanks many times. It is also obvious that rim-fire or center-fire cartridges

can be used to contain the blank charges with corresponding change in the direction of the 40 firing-pin or location of the blank in the outer shell. It is not necessary that the bullet B be fixed in the shell A in order to utilize this part of the invention, although it is much more convenient to so fix it.

If a shell, A, is used having no thinned wall for the reception of the bullet, but having the same bore throughout, it can be used by inserting the same with its blank cartridge in the chamber of the gun and then inserting the 50 bullet in the muzzle of the gun.

Having thus described my improved cartridge, what I claim as my invention, and desire to secure by Letters Patent, is—

1. An inexpensive metallic shell adapted 55 to fit the chamber of a breech-loading gun and constructed substantially as described—that is to say, with thin walls at the outer end for the reception of a large-caliber bullet, and with thickened walls at the other end for the insertion at the head thereof of an ordinary flanged, primed, and powder-filled blank cartridge, substantially as and for the purposes described.

2. A compound cartridge consisting of an 60 external, inexpensive, thick-walled shell and an independent primed and powder-filled blank cartridge confined throughout its length by the solid metallic walls of the external shell, substantially as and for the purposes described.

B. E. VALENTINE.
